(57) **CLAIM**

The ornamental design for a shoe midsole, as shown and described.

DESCRIPTION

FIG. 1 is a perspective view of a shoe midsole.

FIG. 2 is a side view of the shoe midsole of FIG. 1.

FIG. 3 is a side view of the shoe midsole of FIG. 1, from the opposite side as FIG. 2.

FIG. 4 is a front view of the shoe midsole of FIG. 1.

FIG. 5 is a rear view of the shoe midsole of FIG. 1.

FIG. 6 is a top view of the shoe midsole of FIG. 1; and, FIG. 7 is a bottom view of the shoe midsole of FIG. 1.

The broken lines in the figures form no part of the claimed design and surround portions of the shoe midsole that form no part of the claimed design.

1 Claim, 7 Drawing Sheets
